UNITED STATES PATENT OFFICE

THOMAS E. LANGEN, OF BROOKLYN, NEW YORK, ASSIGNOR TO WESTINGHOUSE ELECTRIC & MANUFACTURING COMPANY, A CORPORATION OF PENNSYLVANIA

CONTROLLER FINGER

Application filed December 27, 1926. Serial No. 157,286.

This invention relates to contact fingers primarily designed for use in controllers.

The object of the invention generally stated, is the provision of a contact finger that shall be simple and efficient in operation and readily and economically manufactured.

A more specific object of the invention is to provide for the mounting of the contact member of a contact finger so that it may be set in different positions to assure proper engagement with other contact members.

Another object of this invention is to provide for the mounting of the contact member so that when one face is worn, it may be adjusted to present an unworn contact face.

A further object of the invention is to facilitate the replacement of the contact members so that when a contact member is badly worn, it may be readily replaced without the removal of the other members of the contact finger.

Other objects of the invention will, in part, be obvious, and in part will appear hereinafter.

25 The invention, accordingly, is disclosed in the embodiment thereof, shown in the accompanying drawing, and comprises the features of construction, combination of elements and arrangement of parts that will be exemplified 30 in the structure hereinafter set forth, and the scope of the application of which will be indicated in the claims.

For a general understanding of the nature and objects of the invention, reference should 35 be had to the following detailed description, taken in conjunction with the accompanying drawing in which;

Figure 1 is a view, in side elevation, of a contact finger constructed in accordance with 40 this invention.

Fig. 2 is a top plan view of the contact finger, showing the relation of the different members, and

Fig. 3 is a view in vertical section along 45 the line III—III of Fig. 1.

Referring now to the drawing, 10 designates generally a contact carrier which comprises a member 11, one end of which is shaped to seat on any suitable base or rail 12, 50 and a rigid member 13. As shown, the upper

member 13 of the contact carrier 10 is provided with a cylindrical projection 14 which simulates a shaft. In this particular construction, the member 13 is attached to the member 11 by means of rivets 24, but any other suitable means for connecting these members may be utilized, or they may be made in one piece.

It will be noted that the member 13 is curved so that the projection or shaft 14 extends in a horizontal plane. However, it is to be understood that the particular shape of the upper member 13 of the carrier has no bearing on this invention, and a curved member is illustrated because it is a convenient shape for an embodiment of the invention suitable for drum type controllers.

As will be observed, a contact member 15 is mounted on the contact carrier 10. This contact member includes a cylindrical head 16 and a longitudinal flange member 17 extending laterally. In order to mount the contact member, an opening 18 is provided which extends through the flange member 17 at right angles to the axis of the cylindrical member 16 and which is shaped to receive the shaft 14 of the contact member 10. Therefore, by locating the opening 18 intermediate the ends of the flange member 17, when the contact member 15 is mounted on the shaft 18, it will be symmetrical about any plane extending along the axis of the shaft 14.

The contact member 15 is preferably made from an alloy of copper or some other material which possesses the property of high conductivity along with capacity of withstanding wear.

While in this embodiment of the invention, a contact member having a cylindrical head is illustrated, it will be readily understood that contact members of other shapes may be provided which have suitable contacting faces and which may be disposed symmetrically on the shaft 14 so that when one face of the contact member is worn, it may be rotated either through an angle of 90° or 180° to present an unworn contacting face.

As shown, a shunt 19 is provided for bridging the connection between the contact member 15 and contact carrier 10. The shunt 100

may be of any suitable flexible type and is preferably made of a number of superimposed pieces of copper ribbon, thus providing a laminated member which may be utilized to limit the angular movement of the contact member 15 on the shaft 14.

The shunt may be attached to the flange 17 of the contact member 15 in any suitable manner, and in this particular construction, 10 a clamp 20 is provided. The other end of the shunt is pressed into engagement with the carrier 10 by means of the screws 21 provided for attaching the carrier to the rail 12.

It will be readily understood that the shunt 19 may be utilized for retaining the contact member 15 in position on the carrier 10. By making the shunt of the desired length, provision may be made for permitting a longitudinal movement of the contact member 15 20 on the shaft 14. Therefore provision is made for permitting the contact member to be given reciprocatory and oscillatory movements. A certain amount of oscillatory movement is desirable, since it will permit 25 the contact member 15 to take different positions to accommodate itself to the surface of any controller drum or the like. In Fig. 1, the contact member is shown as riding on the drum 22.

30 In order to permit the contact member to oscillate about a line extending transversely of the carrier 10, the lower member 11 of the carrier is made from some resilient metal such as sheet steel. The resilient member 11 35 may also be used to continually urge the contact member toward the drum 22, thereby assuring a good contact with the drum contact segments, such as 23.

In the embodiment illustrated, the member 40 13 is electrically connected to the member 11 by means of a shunt 25. As will be observed, the shunt 25 is similar in construction to the main shunt 19. However, it is pointed out that the shunt 25 is not always required.

45 When a contact finger of this type has been in use for some time, and the head 16 of the contact member 15 has been worn on one side, it is a simple operation to detach the shunt 19 and rotate the contact member through 180° to present an unworn contact face. When a contact member provided with a cylindrical head 16 is used, it will be seen that a contact with the contact segments 23 which extends throughout the length of the head 16, may be affected.

50 From the above, it will be evident that the inventor has provided a contact finger which possesses long life since the contact member may be rotated to present an unworn face when one of the contacting faces has suffered from wear, and one that may be readily disassembled for the purpose of making replacements.

55 Since certain changes may be made in the above construction and different embodi-

ments of the invention may be made without departing from the scope thereof, it is intended that all matter contained in the above description or shown in the accompanying drawing shall be interpreted as illustrative 71 and not in a limiting sense.

I claim as my invention:

1. In a contact finger, in combination, a contact carrier adapted to be mounted on a base, a contact member mounted on the carrier and disposed for rotary movement about the longitudinal axis of the carrier, and a shunt bridging the junction between the carrier and contact member, said shunt being adapted to retain the contact member loosely 80 in position on the carrier, thereby to permit movement of the contact member along the longitudinal axis of the carrier.

2. In a contact finger, in combination, a contact carrier, a contact member provided with a cylindrical head mounted on the carrier and disposed for oscillatory movement about the longitudinal axis of the carrier and a flexible shunt bridging the junction between the carrier and the contact member, said shunt being detachably connected to the contact member and carrier, thereby to retain the contact member in position on the carrier.

3. In a contact finger, in combination, a resilient contact carrier provided with a 95 cylindrical projection, a contact member provided with an opening for receiving the cylindrical projection provided on the carrier, and a flexible shunt for connecting the contact member to the carrier, said shunt being adapted to permit a predetermined oscillatory movement of the contact member on said carrier projection.

4. In a contact finger, in combination, a contact member having an opening therein, a 105 resilient contact carrier provided with a cylindrical projection adapted for insertion into the opening of said contact member to present a shaft on which the contact member may be rotatably mounted, and a shunt for retaining the contact member in position on the carrier, said shunt being adapted to permit relative movement of the contact member and carrier.

5. In a contact finger, in combination, a contact member provided with a cylindrical 115 head and a laterally extending flange formed integral with the head, said flange having an opening formed therein, a carrier provided with a cylindrical end shaped for insertion into the opening provided in said flange, thereby to permit the contact member to be 120 rotatably mounted on the carrier, and a shunt for retaining the contact member in position on the carrier, said shunt being flexible to permit movement of the contact member relative to the carrier.

6. In a contact finger, in combination, a resilient contact carrier provided with a cylindrical end, a contact member having an opening 130 therein rotatably mounted on the cylind-

drical end of said carrier, said contact member being provided with a cylindrical head to permit the making of contact with any member along a straight line, and a shunt for retaining the contact member in position on the contact carrier, said shunt being flexible to permit the contact member to be set in different positions relative to the carrier.

5 7. In a contact finger, in combination, a contact carrier provided with a cylindrical end, a contact member having an opening for receiving the cylindrical end of the carrier, thereby to permit the contact member to be rotatably mounted on the carrier, said contact member being symmetrical about the end of the carrier, whereby it may be positioned to present different contacting faces, and a shunt for retaining the contact member in position on the carrier, said shunt being flexible, 20 thereby to permit the setting of the contact member in different positions.

8. In a contact finger, in combination, a contact carrier, the end of which is shaped to simulate a shaft, and a contact member provided with a cylindrical head, and a flange extending laterally from the head, said flange being provided with an opening adapted to receive the shaft whereby the contact member may be rotatably mounted thereby to permit 25 the contact member to be set in different positions to present more than one contact face to a member disposed to move in a predetermined path.

9. In testimony whereof, I have hereunto sub-
35 scribed my name this 17th day of December,
1926.

THOMAS E. LANGEN.
